Des. 853 S. W. Gibbs, of Albany, N.Y
Assignor to

G. H. Ball & Co. of Cincinnati, O
Letters Patent No. 853, Dated Dec 23rd 1836.

The Schedule referred to in these Letters Patent and
making part of the same.

To all whom it may concern:

Be it known that I,
S. W. Gibbs of Albany in the County of Albany
and State of New York have invented a new and
useful design for a cooking Stove of which the
following is a full and exact description reference
being had to the accompanying drawings and
to the letters of reference marked thereon. All or -

ornamental parts of panels and corners of panels on
front and side marked A. Ornaments above and
below panels on the side marked B and ornament
on the corners of front and side marked C forming
in combination an ornamental front and side of
said cooking stove.

What I claim is, the combination and ar-
rangement of ornamental figures and forms rep-
resented forming the ornamental design for the plates
of a cooking stove. In witness whereof, I have here-
unto subscribed my name the first day of October
eighteen hundred and fifty six.
